UNITED STATES PATENT OFFICE.

EVERARD J. APPLETON, OF CINCINNATI, OHIO.

DESIGN FOR A PUZZLE-BOARD.

SPECIFICATION forming part of Design No. 34,556, dated May 21, 1901.

Application filed April 17, 1901. Serial No. 56,318. Term of patent 3½ years.

To all whom it may concern:

Be it known that I, EVERARD J. APPLETON, of Cincinnati, Ohio, have invented and produced a new and original Design for a Puzzle-Board, whereof the following is a specification.

My design may be best understood from the accompanying drawings, in which I have illustrated it, and in which—

10 Figure 1 is a plan. Fig. 2 is a cross-section on the line 2 2 of Fig. 1.

In the figures, 1 represents the base of the puzzle-board, surrounded by walls 2 2. 3 is a raised center of the base surrounded by a 15 similarly-raised causeway 4, from which it is separated by a channel 5, which terminates at 6, where the causeway and center communicate.

7 is a ledge flush with the surfaces of the 20 causeway 4 and the center 3, extending around the walls 2 and separated from the causeway

4 by a channel 8, but connected with the causeway by bridges 9, which span the channel 8.

The channel 5 extends nearly around the 25 center 3 from the point 6 and then communicates with the channel 8, which extends without a break clear around the center and causeway.

As shown, the main features of my design 30 consist in the raised center, with the causeway communicating therewith at one point and the ledge communicating with the causeway at several points.

I claim—

35 The design for a puzzle-board as herein shown and described.

EVERARD J. APPLETON.
